CLAIM

The ornamental design for a feeder for supplying a fixed quantity of particles, as shown and described.

DESCRIPTION

FIG. 1 is a front elevational view of a feeder for supplying a fixed quantity of particles, showing our new design; FIG. 2 is a rear elevational view thereof; FIG. 3 is a top plan view thereof; FIG. 4 is a bottom plan view thereof; FIG. 5 is a left side elevational view thereof; FIG. 6 is a right side elevational view thereof; FIG. 7 is a cross-sectional view taken along line 7—7 of FIG. 3; and, FIG. 8 is a right side elevational view, partially in cross section, showing the design in use, the broken line showing being for illustrative purposes only, and forming no part of the claimed design.
